ADJUSTABLE MOUNTING BASE FOR A PATIENT SUPPORTING UNIT

George A. Fortnam, Des Moines, Iowa, assignor to
Den-Tal-Ez Mfg. Co., Des Moines, Iowa

Filed Aug. 25, 1972, Ser. No. 283,978

Term of patent 14 years

Int. Cl. D24—01

U.S. Cl. D83—1 E

FIG. 1

FIG. 2

FIG. 3FIG. 4FIG. 5FIG. 1 is a perspective view looking toward one side of my new design for an adjustable mounting base for a patient supporting unit;

FIG. 2 is a perspective view looking toward the opposite side shown in FIG. 1;

FIG. 3 is a top plan view;

FIG. 4 is a front view; and

FIG. 5 is a rear view.

I claim:

The ornamental design for an adjustable mounting base for a patient supporting unit, substantially as shown.
